UNITED STATES PATENT OFFICE.

IVAN FOX, OF LANSDOWNE, PENNSYLVANIA.

DESIGN FOR A BLANK FOR NOSE-PIECES FOR EYEGLASSES OR SPECTACLES.

SPECIFICATION forming part of Design No. 32,651, dated May 15, 1900.

Application filed April 2, 1900. Serial No. 11,265. Term of patent 7 years.

To all whom it may concern:

Be it known that I, IVAN FOX, a citizen of the United States, residing at Lansdowne, in the county of Delaware, in the State of Pennsylvania, have invented and produced a new and useful Design for a Blank for a Nose-piece for Eyeglasses and Spectacles, of which the following is a specification, reference being had to the accompanying drawing, forming part thereof.

The accompanying drawing is an illustration in face elevation of a blank for a nose piece showing my new design.

As shown in the drawing, the leading or material feature of my design consists of an arm provided body A, the upper end of which is equipped with two branches B C which constitute continuations of said body.

The branches exist in substantially the

same plane as the body, and slightly diverge 20 from each other from their inner to their outer ends, said body and branches having somewhat of a Y-shaped appearance.

The arm D, which is in substantially the same plane as the body, projects from its side 25 or edge, as shown.

Having described my invention, what I claim as new, and desire to secure by Letters Patent, is—

The design for a blank for a nose piece as 30 herein shown and described.

In testimony that I claim the foregoing as my invention I have hereunto signed my name this 6th day of September, A. D. 1899.

IVAN FOX.

In presence of—

F. NORMAN DIXON,
THOS. K. LANCASTER.
